DESIGN FOR A WREATH

Abraham J. Barocas, Brooklyn, N. Y.

Application May 21, 1935, Serial No. 56,939

Term of patent 14 years

To all whom it may concern:

Be it known that I, Abraham J. Barocas, a citizen of the United States, residing at Brooklyn, in the county of Kings and State of New York, have invented a new, original, and ornamental Design for a Wreath, of which the following is a specification, reference being had to the accompanying drawing, forming a part thereof.

Fig. 1 is a front view of a wreath showing my new design, the portion shown in detail being continuous around the entire periphery of the wreath.

Fig. 2 is an edge view thereof.

I claim:

The ornamental design for a wreath, as shown.

ABRAHAM J. BAROCAS.
